HOLDER FOR PAPER CUPS

Herman Carew, Easton, Pa., assignor to Dixie Cup Company, Easton, Pa., a corporation of Delaware

Application September 28, 1948, Serial No. 51,520

3 Claims. (Cl. 65—61)

1

This invention relates to improvements in a holder for paper cups, the invention being highly desirable for use in connection with the dispensing of sodas, soft drinks, and other beverages or confections in fountains, restaurants, and similar establishments, although the invention will have other uses and purposes as will be apparent to one skilled in the art.

The instant application is a continuation-in-part of my previously filed application entitled "Holder for Paper Cups," filed August 26, 1947, Serial No. 770,674.

In soda fountain and similar usage today, it is desired to have a holder for paper cups which will automatically lock the cup within the holder and retain that cup against accidental dislodgement before, during and after use of the cup, and until the attendant forcibly removes the cup from the holder to dispose of it. It is also required that in order to lodge the cup within the holder and have it anchored therein only a relative axial movement between the holder and cup is necessary. There must be no movable parts to be manipulated by hand, no twisting motions of the holder relatively to the cup or vice versa, no adjustments to be made, and at the same time the holder itself must be constructed so that it can be periodically cleansed to a thorough degree. It is also preferable that the cup be positively engaged by the holding means in the holder upon a light axial movement of the holder relatively to the cup. That is because the cups are preferably kept in a dispenser, the holder placed over the protruding end of the cup, and that particular cup withdrawn from the dispenser, so the attendant never need touch the cup with his hand at any time until the cup is ready to be discarded.

With holders of this type the cup engaging means inside the holder obviously perform most of the work and after long and repeated usage those engaging means may become damaged or dulled so that they do not work as effectively as desired. Heretofore, the only thing to do in that regard was to replace the holder with a new holder, an expensive procedure.

It is therefore an important part of the instant invention to provide a cup holder that will operate as described above, and wherein the cup engaging means may be simply removed and re-

placed with new engaging means in a very facile manner and very economically.

Another object of the invention is the provision of a cup holder with a cup receiving cavity therein, and a groove inside the holder, there being a cup retaining element in said groove, and another member disposed in the groove below that retaining element.

Still another object of this invention resides in the provision of a holder for paper cups having a cup receiving cavity therein, as well as a groove in the body of the holder, one groove defining wall being of larger diameter than the opposite and corresponding wall, with a cup engaging element of less size than the larger groove wall disposed in the groove, and simple snap means engaged in the groove below that element to retain the element in proper position.

Still a further object of the invention resides in the provision of a cup holder for paper cups, having a cup receiving cavity with an opening in the bottom thereof, the wall of the holder having a groove therein immediately below the opening with the wall on the outer side of that groove having an opening of greater diameter than the opening in the wall on the inner side, and a cup engaging element in the form of a disc-like member carrying resilient teeth projecting inwardly therefrom seated in the groove, with a simple spring ring snapped into the groove below the cup engaging element to hold the latter in position.

While some of the more salient features, characteristics and advantages of the instant invention have been above pointed out, others will become apparent from the following disclosures, taken in conjunction with the accompanying drawing, in which:

Figure 1 is a side elevational view of a paper cup holder embodying principles of the instant invention in operative association with a cup;

Figure 2 is an enlarged fragmentary central vertical sectional view through the lower portion of the holder and cup of Fig. 1; and

Figure 3 is a greatly enlarged bottom plan sectional view taken substantially as indicated by the line III—III of Fig. 2 looking in the direction of the arrows.

As shown on the drawings:

In the illustrated embodiment of the instant

invention there is shown a holder 1, which may be roughly said to be generally of hour glass shape. The upper portion of the holder body tapers inwardly to a constricted throat at 2 and then flares outwardly to provide a hollow base 3. The body part of the holder may be made of any suitable material, such as a molded plastic material, or the holder may very suitably and satisfactorily be made of metal.

The upper part of the holder embodies a cup receiving cavity or socket 4, and in the illustrated embodiment the holder is shown designed to accommodate a conical paper cup. As seen best in Fig. 2 there is an opening in the bottom of the cup receiving cavity through which the apical portion of a paper cup 5 may extend, as indicated at 6.

With reference more particularly to Figs. 2 and 3, it will be seen that immediately below the opening in the bottom of the cup receiving cavity, the wall of the holder is provided with an annular groove 7, and the lower groove defining wall 8 extends inwardly less distance than the upper groove defining wall 9, which presents a laterally extending face against which a retaining element may be disposed, as clearly seen in Fig. 2. A disc-like cup engaging element 10 may be placed in the groove 7, and this element has an outer marginal substantially flat portion which is of less diameter than the opening through the lower groove defining wall 8 so that the holding or engaging element 10 may readily be seated against the upper groove defining wall 9 through this opening in the wall 8.

The general construction of the cup engaging element 10 is best seen in Fig. 3. Preferably this element is made of thin spring steel, and is of the general character as the element more specifically described and claimed in my aforesaid copending application. A series of radial slots 11 are provided in the disc-like element 10 to define resilient cup engaging teeth 12, which teeth are preferably inclined downwardly as seen best in Fig. 2. In the illustrated instance, the teeth 12 are so shaped as to define a central opening of generally square shape. As seen in Fig. 2, the teeth extend inwardly beyond the wall defining the opening at the bottom of the cup receiving cavity 4, so that it is impossible for a conical cup to be properly seated within that cavity without the teeth having a positive frictional engagement with the wall of the cup. The teeth being resilient bend outwardly to some extent when the cup enters the holder or the holder is passed over the bottom of the cup, and their engagement is sufficient to distort the wall of the cup into substantially a square configuration as indicated at 13 in Fig. 3. The downward slope or bend of the teeth effects a biting engagement that becomes more positive upon a pull tending to lift the cup out of the holder. The engagement is obviously sufficiently firm to prevent any accidental dislodgement of the cup, by way of a draft of air, by way of the rim of the cup sticking to a customer's lip, or in some similar fashion. A definite pull is required to remove the cup from the holder against the action of the teeth, but an attendant may remove the cup by a simple relatively quick jerk when the cup is to be disposed of or discarded, because it makes no difference if any injury then results to the cup.

In order to retain the cup engaging element 10 properly seated in the groove of the holder, I have provided a spring ring 14 having spaced apart and enlarged end portions 15 and 16.

This ring is preferably flat, having a substantially rectangular cross section as seen in Fig. 2. Thus, it can more readily seat within the groove 7. Each of the expanded end portions 15 and 16 is provided with a transverse aperture 17 therethrough, and it is a simple expedient to engage parts of a tool through such aperture and contract the ring to remove it from the holder, the ring normally having a tendency to expand to a diameter greater than the opening through the wall 8 and seat positively against the outermost wall of the groove 7.

Consequently, should the cup engaging member 10 become damaged in any way and should it be desired to replace that member with a new one, it is a simple expedient to contract and remove the ring, permit the cup engaging element to drop out. The new one may be placed in, and it is as equally simple and expedient to snap the ring back in the groove. Thus, the life of the holder is greatly prolonged because the only part with any reasonable likelihood of ever becoming out of order may be readily replaced and very economically. It will be noted from the showing in Fig. 3 that the retaining ring 14 preferably engages the cup holding member 10 outwardly beyond the termination of the slots 11, so that the retaining ring does not interfere in any manner with the resiliency or the spring action of the cup engaging fingers 12.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A holder for a paper cup, including a tubular body part having a cup receiving socket therein with an opening at the bottom thereof, said body part having a groove therein with the groove defining wall on one side extending to said opening and the corresponding wall on the other side having a larger opening therein, a disc-like cup holding member having a flat marginal portion seated in the groove and inwardly directed resilient cup engaging teeth, said member being of less diameter than the larger opening, and a flat split-ring having spaced enlarged ends engaged in said groove to retain said holding member in position, the enlarged ends of said split-ring each having a transverse aperture therethrough to accommodate a removing tool.
2. A holder for a conical paper cup, including a tubular body part having a cup receiving socket therein with an opening in the bottom through which the apical portion of a cup extends when the cup is seated in the holder, a laterally extending annular face in said holder adjacent said opening, a thin metallic disc-like member having an open central portion with a plurality of inwardly extending and downwardly sloping resilient teeth to yield with an entering cup and biting engage the wall of the cup to resist a tendency of the cup to leave the holder, said member being disposed against said face, and a centrally open smooth surfaced element frictionally seated in said holder to hold said member in position.
3. A holder for a conical paper cup, including a tubular body part having a cup receiving socket therein with an opening in the bottom through which the apical portion of a cup extends when the cup is seated in the holder, a

5

laterally extending annular face in said holder below said opening, a relatively thin metallic disc-like member having a flat annular margin disposed against said face, and a plurality of downwardly sloping resilient teeth extending inwardly from said margin for edgewise biting engagement with the apical wall portion of a cup, and a centrally open metallic element mounted in said holder below said member to hold the same in place.
